UNITED STATES PATENT OFFICE.

GEORGE W. KERR, OF RACINE, WISCONSIN.

CURTAIN-WINDOW.

1,345,602.

Specification of Letters Patent. Patented July 6, 1920.

Application filed May 2, 1919. Serial No. 294,148.

To all whom it may concern:

Be it known that I, GEORGE W. KERR, a citizen of the United States, and resident of Racine, in the county of Racine and State of Wisconsin, have invented new and useful Improvements in Curtain-Windows, of which the following is a description, reference being had to the accompanying drawings, which are a part of this specification.

10 The invention relates to curtain windows, more particularly for automobile curtains.

One of the objects of this invention is to provide a curtain window construction in which the outside marginal frame for the 15 glass is made in one piece of metal which may be finished to produce a neat and ornamental appearance.

Another object of the invention is to provide an economical curtain window construction which may be readily and quickly 20 installed.

The invention further consists in the several features hereinafter set forth and more particularly defined by claims at the 25 conclusion hereof.

In the drawings: Figure 1 is an elevation view of the window embodying the invention, parts being broken away; Fig. 2 is a section taken on the line 2—2 of Fig. 1.

30 In the drawings the numeral 3 designates the curtain side wall which is made of the usual curtain cloth, 4 the inner lining of the curtain, 5 the usual strips of cotton webbing, and 6 the wooden window frame secured to the spaced strips of webbing 5 by tacks 7 or other suitable fastening means.

The wood frame 6 has a small oval opening 8 therein and a larger oval opening 9 with a shoulder 10 between these openings. 40 The inner lining 4 is turned in to form a facing for the opening 8 and is secured to the frame by tacks 11, while the side wall 3 is brought down into an oval recess 12 in the wood frame and is then turned in to form a facing for the opening 9, being secured to the frame by tacks 13.

The numeral 14 designates the glass light, 15 the outside glass retaining member and 16 the inside retaining member for the glass.

50 The retaining member 15 consists of a single piece of metal in the form of an oval ring of T-shape in cross section, the outer oval shouldered portion 15' resting on the side wall facing adjacent the recess 12, the 55 web portion 17 of the T being disposed adjacent the side wall facing for the opening 9,

with its inner periphery lying flush with the lining-facing for the opening 8, the retaining frame 15 being secured to the frame 6 by tacks 18 passing through the web and 60 into the frame 6. The head 19 of the T is rounded to produce a finished appearance and it may be nickel-plated and polished for ornamental purposes.

The retainer member 16 consists of a wood 65 strip 20 having a fabric covering 21 and adapted to be secured to the wooden frame 6 by tacks or upholstery nails 22.

After the marginal frame 15 is secured in place the glass is inserted so as to bring its 70 marginal edge portion 23 into contact with the oval shouldered portion 24 of the retainer frame 15, and then the retainer member 16 is brought up against the other side of the edge of the glass, said member being 75 secured by tacking the strip to the frame 6 and cutting the edges of the strip so that they will be properly joined together to form an oval ring.

With the above construction the window 80 light may be quickly installed and the one piece metal frame 15 produces a neat and ornamental appearance to the window and may be easily secured to the frame.

What I claim as new and desire to secure 85 by Letters Patent is:

1. In an automobile curtain window, the combination, with a wooden frame having a visional opening and an outside fabric with an inner fabric lining attached to said frame, of a marginal metal frame having a continuous inwardly projecting flange forming a continuous metal frame lining for the visional opening, a transparent member inclosed within the limits of the flange and having its outer surface engaging the inner surface of the marginal frame, means for securing the marginal frame to the wooden frame, and an inner retainer member secured to the frame within the opening and 100 engaging the inside of said transparent member.

2. In a curtain window, the combination, with the curtain and a wooden window frame secured thereto and having a visional 105 opening, of a marginal metal frame having an inwardly projecting flange projecting into the visional opening, a transparent member inclosed within the limits of the flange and having its outer surface engaging 110 the inner surface of the marginal frame, means passing laterally through the flange

and into the wooden frame at the opening to secure the metal frame in place, and an inner retainer member secured to the frame within the opening and engaging the inside 5 of said transparent member.

3. In a curtain window, the combination, with the curtain having a side wall and inner lining, of a wooden frame having a small opening and a large opening with a 10 shouldered portion between said openings, means securing the edge of the lining to the frame over the small opening, means securing the edge of the side wall to the frame over the large opening, an outside 15 one-piece metal retainer having an inwardly extending continuous flange disposed adjacent the side wall facing lining the large opening, means passing through the flange to secure said retainer to the frame, a window light having one side of its marginal portion abutting against the inner side of the retainer, and retaining means secured to the frame in the small opening and abutting 20 against the other side of the window light.

4. In an automobile curtain window, the

combination of a wooden frame having a visional opening, an outside fabric with an inner fabric lining attached to the frame within the opening, a marginal metal frame 30 having a flanged portion projecting into the visional opening and attached to the frame within the opening, a transparent member disposed within the limits of the flanged portion of the marginal frame and 35 having its outer surface engaging the inner surface of the marginal frame, an inner retainer attached to the frame within the opening and engaging the inside of said transparent member, fastening means securing 40 the outside fabric, inner fabric lining, metal frame and retainer to said wooden frame, all of said fastening means attachable through the visional opening and passing into the inner edge of the wooden frame. 45

In testimony whereof I affix my signature in presence of two witnesses.

GEORGE W. KERR.
